CLAIM

The ornamental design for a shoe with heel and outsole patch, as shown and described.

DESCRIPTION

FIG. 1 is a perspective view of an embodiment of my new design of a shoe with heel and outsole patch, in which the outsole patch is hatched using the USPTO convention of horizontal lines for blue (e.g., Pantone 277-Pantone 314, any one of Pantone 317-Pantone 320, Pantone 325 or Pantone 326, any one of Pantone 532-Pantone 552, any one of Pantone 628-Pantone 662, Pantone 801, Pantone 808, any one of Pantone 2702-Pantone 2708, Pantone 2717 or Pantone 2718, Pantone 2727 or Pantone 2728, Pantone 2747 or Pantone 2748, Pantone 2757 or Pantone 2758, Pantone 2767 or Pantone 2768, any one of Pantone 2905-Pantone 3165, any one of Pantone 3242-Pantone 3278, any one of Pantone 5395-Pantone 5435, any one of Pantone 7453-Pantone 7477, any one of Pantone 7541-Pantone 7547, or any one of RAL 5000-RAL 5026);

FIG. 2 is a front view of the design of FIG. 1;

FIG. 3 is a back view of the design of FIG. 1;

FIG. 4 is a first side view of the design of FIG. 1;

FIG. 5 is a second side view of the design of FIG. 1;

FIG. 6 is a top view of the design of FIG. 1; and,

FIG. 7 is a bottom view of the design of FIG. 1.

The broken lines illustrate features of the shoe that form no part of the claimed design.
